(57) **ABSTRACT**

An exercise device and method of use are provided which allows the user to exercise and strengthen the spinal and abdominal muscles. The device includes a telescoping stanchion which is tension loaded with resilient bands which can be used in multiples to increase the tension and resistance needed. The height of the stanchion can be adjusted as well as its angularly position relative to a base having a seat thereon.

ABDOMINAL EXERCISE DEVICE AND METHOD

BACKGROUND OF THE INVENTION

1. Field of the Invention

The invention herein pertains to a device for exercising and building strength for the human body, and it is particularly concerned with exercise for the abdominal and spinal muscles.

2. Background and Objectives of the Invention

Many exercise machines have been developed in recent years for strengthening and exercising various muscles of the human body. For example, abdominal muscles can be strengthened using the devices as set forth in my prior U.S. Pat. Nos. 5,766,118 and 5,871,424.

However, such prior art devices do not adequately exercise the abdominal and spinal muscles simultaneously. Also, such prior art devices do not have the adjustability needed for specific muscle areas. In addition, such prior art devices are not built to withstand the wear and tear of continuous use in an exercise gym or similar commercial environment.

Thus, with the disadvantages and problems associated with prior art devices, it is an objective of the present invention to provide an exercise device which is easy to learn to use and adjust for an individual's particular needs.

It is also an objective of the present invention to provide an exercise device which includes a movable stanchion which is adjustably joined to a base.

It is yet still another objective of the present invention to provide an exercise device and method which will allow the user to exercise and strengthen the abdominal and spinal muscles simultaneously.

It is another objective of the present invention to provide an exercise device which includes resilient bands which can be affixed to the movable stanchion for resistance purposes.

Various other objectives and advantages of the present invention will become apparent to those skilled in the art as a more detailed description is set forth below.

SUMMARY OF THE INVENTION

An exercise device and method are presented whereby a user can readily strengthen the abdominal and spinal muscles. The device includes means for adjusting the device to one's particular needs and also allows for increasing the tension desired by the use of multiple resilient bands. A metal frame including a seat is affixed to a movable stanchion. The stanchion can be adjusted to the approximate shoulder height of the sitting user. The stanchion includes an arm support at the top whereby the user's forearms press the arm support downwardly, causing the stanchion to descend under tension. The greater the decent, the greater the tension and resistance. The stanchion is adjustable to various angles from the base from an angle of zero degrees (vertical) to an approximate horizontal position of about ninety degrees with the use of a removable pin.

During exercises, as the stanchion is depressed while in its vertical posture, the abdominal muscles are contracted whereas the back or spinal muscles are elongated. Likewise, when arm pressure is released from the stanchion, the abdominal muscles elongate or expand and the spinal or back muscles contract.

BRIEF DESCRIPTION OF THE DRAWINGS

FIG. 1 demonstrates a perspective view of the exercise device of the present invention;

FIG. 2 shows a front elevational view of the device as shown in FIG. 1;

FIG. 3 pictures a right side elevational view of the device as shown in FIG. 1;

FIG. 4 features a schematic view of one configuration of the device in use prior to the user applying pressure to the stanchion;

FIG. 5 depicts the device as seen in FIG. 4 with the stanchion depressed and the abdominal muscles of the user in a contracted form;

FIG. 6 illustrates another schematic configuration of the exercise device of FIG. 1 with the stanchion positioned at an approximate sixty degree angle from the vertical; and

FIG. 7 shows the configuration as seen in FIG. 6 with the stanchion depressed and the back muscles elongated.

DETAILED DESCRIPTION OF THE PREFERRED EMBODIMENTS AND OPERATION OF THE INVENTION

For a better understanding of the invention and its method, turning now to the drawings, FIG. 1 demonstrates the preferred form of exercise device 10 which includes movable stanchion 11 affixed to base 12 with seat 13 mounted thereto. Arm support 14 is a substantially horizontal member formed from metal and may optionally be covered with foam rubber or the like (not seen) for comfort purposes as desired. Stanchion 11 includes resilient band retainers 15, 15' and 16, 16'. Band retainers 15, 15' slide within slots 25, 25' (25' not shown) on opposite sides of upper stanchion section 19. As further seen, stanchion 11 includes first section 17 which may be formed of tubular steel, second section 18 also formed from tubular steel and third or upper section 19 all formed from tubular steel and sized for telescoping engagement. As would be understood band retainers 16, 16' are affixed such as by welding to upper section 19 whereas band retainers 15, 15' are affixed to second section 18. Upper section 19 telescopically slides along second section 18 during exercising. Bands 20 (FIG. 2) are formed from durable rubber or other suitable elastic polymeric materials. The height of stanchion 11 is adjustable by manually removing pin 21 and placing it in different apertures 22 which are positioned in first section 17, by aligning aperture 23 of second section 18 therewith depending on the particular height desired and comfort of the user.

Stanchion 11 can also be adjusted to various vertical positions as determined by pin 26 placement in openings 24A, 24B, 24C or 24D. Openings 24A-D allow adjustment of stanchion 11 in approximate thirty degree increments from the vertical position (zero degrees) as shown in FIG. 3 to a horizontal position (ninety degrees not shown). Pin 26 is manually removed from openings 24A-D, 24A'-D' (not seen) within stanchion guides 28, 28'. Stanchion 11 rotates around axle 36 mounted in guides 28, 28' which are rigidly affixed such as by welding or the like to horizontal base member 29 which is attached to seat post 30. Seat post 30 is affixed to U-shaped base frame 31 which as shown in FIG. 1, includes telescoping feet 32, 32'. Feet 32, 32' can be extended or retracted as needed for stability, depending on the particular exercise and the angular position of stanchion 11. Feet 32, 32' are extended to their maximum when stanchion 11 is in a horizontal configuration. Feet 32 and 32' are joined to horizontal member 33 which in turn is affixed at the bottom of seat post 30.

In use, stanchion 11 can be positioned in a vertical posture by use of openings 24A, 24A' as shown in FIG. 3 such as by user 35 in FIG. 4. User 35 then places his folded arms on arm

support **14** and by pressing downwardly, as shown in FIG. **5** stanchion **11** is depressed while the abdominal muscles are contracted and the spinal or back muscles are extended. Thereafter, by releasing pressure on arm support **14**, stanchion **11** returns to its original upright position as shown in FIG. **4** by resilient bands **20**.

In FIG. **6** opening **24C** is used in stanchion guides **28, 28'** for a different configuration. By changing the angle of stanchion **11**, some different muscles are employed in the depression of stanchion **11** as seen in FIG. **7**. Again, once stanchion **11** is released, it returns to its extended posture as shown in FIG. **6** at an angle of approximately sixty degrees from the vertical. Full details of exercise device **10** are not seen in FIGS. **4-7** as these figures are merely schematic representations for illustrative purposes of its use.

The method of use of exercise device **10** as described above will vary depending on the particular user and the particular goals to be accomplished. More or less resilient bands can be used as needed and the configuration adjustments to exercise device **10** allow infinite variety.

The illustrations and examples provided herein are for explanatory purposes and are not intended to limit the scope of the appended claims.

I claim:

1. An exercise device for the abdominal and spinal muscles comprising a base, a vertical seat post, said seat post affixed to said base, a seat, said seat affixed proximate the top of said seat post, a movable, vertically adjustable stanchion, a horizontal member, said horizontal member affixed to said seat post proximate said seat, said stanchion pivotally joined to said horizontal member in opposing relation to said seat,

a resilient member, said resilient member attached to said stanchion to apply a resistive force as said stanchion is moved whereby a user can sit on said seat and urge said stanchion in a downward direction with his arms.

2. The exercise device of claim **1** further comprising an arm support, said arm support attached to the top of said stanchion, said arm support having a flat upper surface for comfort as force is applied thereto.

3. The exercise device of claim **1** wherein said stanchion **10** comprises a first section, said first section pivotally attached to said horizontal member, a second section, said second section telescopically joined to said first section, a third section, said third section resiliently joined to said second section, and an arm support, said arm support attached to said third section.

4. The exercise device of claim **3** wherein said first section is incrementally telescopically joined to said second section as desired for the particular height of the user.

5. The exercise device of claim **3** wherein said stanchion **20** is formed of tubular materials.

6. The exercise device of claim **3** further comprising a resilient band, said band attached to said first and said second sections.

7. The exercise device of claim **1** further comprising a stanchion guide, said guide attached to said horizontal member to allow said stanchion to be angularly adjusted to said horizontal member.

8. The exercise device of claim **1** wherein said base **30** comprises a base frame, an adjustable foot, said foot affixed to said base frame.
